TRANSMISSION LINE SUPPORT

Helmut Brueckmann, Little Silver, N. J., assignor to the United States of America as represented by the Secretary of the Army

Application January 9, 1951, Serial No. 205,165

2 Claims. (Cl. 174—43)

(Granted under Title 35, U. S. Code (1952), sec. 266)

The invention described herein may be manufactured and used by or for the Government for governmental purposes, without the payment of any royalty thereon.

The present invention relates to a means for compensating for the capacity of the insulator by adding an inductance in the circuit.

More particularly, the present invention relates to an insulator for transmission lines or antennas that compensates for its effective capacity in the line at normal operating frequencies, and also to an insulator with increased physical strength and increased breakdown voltage.

In all types of support insulators presently used for open-wire transmission lines, the construction design is based chiefly on the principle of keeping the insulator capacity as small as possible. As a result, the physical strength and the breakdown voltage of these insulators suffer more or less. The described equalization method permits the design of a new type of support insulator with increased physical strength and breakdown voltage.

It is, therefore, an object of this invention to provide a transmission line insulator.

It is a further object of this invention to provide an insulator that is compensated for its inherent capacity.

It is a further object of this invention to provide an insulator that has unusually low losses.

It is a further object of this invention to provide an insulator that combines exceptional physical strength with unusually low losses at certain frequencies.

It is a further object of this invention to provide a transmission line of substantially constant impedance throughout its entire length.

The present invention is best understood by reference to the following specification and the drawings in which Figs. 1 and 2 are views of a section of a two wire transmission line supported by insulators embodying the principles of this invention.

Figs. 3 and 4 are views of another section of transmission line, showing where the line enters and leaves the support at other than a 180° angle.

Referring now to Fig. 1, the four strain insulators 5, 6, 7 and 8 are identical in construction and each consists of a cylindrical or prismatical rod 9 of insulating material, preferably ceramic, with metallic caps 10, 11 on each end. Additionally, a corona shield 12 is clamped on this rod between the caps. The two stand-off insulators 15, 16 consist also of a cylindrical or prismatical rod 17 of insulating material, with a metallic cap 18 on one end and some kind of flange 19 on the other end as seen in Fig. 2. All insulators are mounted on a crossarm 21, preferably made of structural steel, which can be mounted horizontally on top of a pole (not shown in Fig. 1) in the usual manner. The free ends of the insulators 5, 6, 7 and 8 support the line wires 23, 24, 25 and 26 respectively and the jumpers 28, 29, 30 and 31, seen more clearly in Fig. 2. Except in some cases mentioned below, the wire diameter of the jumpers can be the same as that of the line. Single-layer solenoid coils 33, 34, 35 and 36 are added to these insulators and are preferably wound around the ceramic rods of the strain insulator so that they form one mechanical unit with them. One end of each coil is connected to the cap 10 next to it and to the corresponding line wire 25; the other end is connected to the corona shield 12 and the jumper 30. The jumpers should be somewhat loose so that they do not take any part of the heavy strain in the line wires. The two stand-

off insulators 15 and 16 are supposed to prevent swinging of the jumpers but can be omitted if desired.

The capacities of the caps and corona shields depend on their physical dimensions and the dielectric constant of the insulating material used for the rods. These capacities can be measured. Consequently, the inductance of the coils can be calculated to give, in combination with the capacity of the insulators, a characteristic impedance of the entire support equal to the characteristic impedance of the line. Preliminary calculations, based on an estimated insulator capacity of approximately $10 \mu\text{uf}$. have shown that the coil dimensions required to create the necessary inductance (in order of $1 \mu\text{hy}$.) are quite practical, and would be, for example, 10 turns with a 1 inch diameter core.

With some of the presently used types of support insulators, it is difficult to maintain accurately the separation of the line wires, if they are used to support the line at a point where the horizontal direction of the line changes. The insulator arrangement of Fig. 1 eliminates these difficulties, since the separation of the eyebolts 40, 41, 42 and 43 with which the strain-insulators 5, 6, 7 and 8 are fastened to the crossarm 21 can be readily increased in order to maintain the separation of the line wires accurately. Of course, the location of the stand-off insulators 15 and 16 on the crossarm and their separation has to be changed correspondingly. It seems advisable to provide a series of holes in crossarms which are supposed to be used for line turns. This would permit an increase in distance of the eyebolts and the location of the stand-off insulators along the crossarm in small steps, corresponding to certain small steps in the turn angle of the line.

However, due to the fact that the line wire at the outer side of the turn angle tends to be longer than the line wire at the inner side of the turn angle, this arrangement is not practical for large turn angles. For turn angles exceeding say, 30°, the arrangement of Figs. 3 and 4 would be advantageous. In this arrangement, wherein like elements have the same numbers as their counterparts in Figs. 1 and 2, the transmission lines 23, 24, 25 and 26 are connected through coils 33, 34, 35 and 36 to each other by the single jumpers 40 and 41. One pair of transmission lines is brought in to the support 45 at one level 46 and the other at another level 47. The insulators are also slightly staggered, and this, together with the change of level makes it possible to maintain the spacing and the length of the transmission line constant throughout the turn. This adds to the uniform impedance characteristics of the transmission line, where formerly a change in line spacing or length was considered unavoidable at any change in direction.

It is also noted, that in this turn arrangement, the jumper wires are held taut in their proper spacing by the compensated insulators 5—6 and 7—8, thereby avoiding the difficulties of loose bridging or added spacers or supports. The only considerable source of error in this turn arrangement is in the basic support insulators, which are, of course, compensated by the addition of inductance, as described earlier.

The insulator arrangement of Figs. 1 and 2 can be adapted easily for use as an entrance insulator assembly at points where the line enters into a building. For this purpose, the stand-off insulators 15 and 16 are replaced by common type entrance insulators, and the strain-insulators 5 and 7 are mounted to the wall of the building, instead of to a crossarm. If the capacity of the entrance insulators were different from that of the stand-off insulators, the inductance of the coils 33 and 35 would have to be changed correspondingly. However, from the point of view of standardization, it would be preferable to use the same size coils in all cases and to correct any unbalance by changing the wire diameter of the jumpers 28 and 30.

The details of a system for compensating for the capacity of an insulator by a decrease in the size of the appropriate jumpers are given in my co-pending application for an improvement in "Transmission Line," Serial No. 200,271, filed December 11, 1950, now abandoned. Since the difference in insulator capacity in this case

3

would probably be small, the corresponding difference in wire diameter would also be small.

Another way to further standardization is to design the coil for the greatest insulator capacity which occurs in practice, then that part of the coil which is in excess of the optimum value for the particular application can be short-circuited, or the amount of capacity that is needed to equal the capacity for which the coil is designed can be added, for example, by setting a number of connectors on the jumpers.

The physical strength and the breakdown voltage of this insulator arrangement can be made considerably better than that of the presently used insulator systems. It is estimated that the tension in the wires can be at least doubled without increasing the danger of breaking the insulators. This means that the span of the transmission line between adjacent poles (present practice is approximately 90 feet) can be increased by at least 40%, if the same sag of the wires that is presently accepted is permitted. In other words, one pole in about 270 feet of transmission line can be saved in this way. In respect to cost and shipping weight, a comparison could be based on two poles with two of the suggested insulator arrangements on one hand, and three poles with three of the conventional insulator arrangements on the other hand. It is to be expected that such a comparison would favor the new design. Not only would the line have fewer sources of impedance mismatch, these sources would be effectively compensated.

As a by-product, the suggested insulator arrangement gives a well-defined filter action in the transmission of harmonics of the operating frequency. From this point of view, it is desirable, in long range communications, for example, to have a cutoff frequency of about 30 mcs. This corresponds to a lumped capacity of about $17 \mu\text{f}$. and an inductance of about $6 \mu\text{h}$. (1.5 μh . for each coil).

While a preferred embodiment of this invention has been described here, other embodiments will be obvious to those skilled in the art.

What is claimed is:

1. At a turn in a transmission line, a first pair of uni-

- 5 formly spaced conductors in a first plane, a second pair of similarly spaced conductors in a second plane substantially parallel to said first plane, and a third pair of similarly spaced jumper conductors in a third plane substantially perpendicular to said other planes, said jumper conductors connecting said first pair of conductors to said second pair of conductors said first and second pairs of conductors meeting said third plane at substantially equal angles, and said third pair of conductors meeting said

10 first and second planes at substantially the same angle, whereby said jumper wires are of equal length and the spacing, length, and characteristic impedance of said transmission line is substantially constant throughout said turn.

15 2. At a turn in a transmission line, a first pair of uniformly spaced conductors in a first horizontal plane, a second pair of similarly spaced conductors in a second horizontal plane, and a third pair of similarly spaced jumper conductors in a third vertical plane, said jumper conductors connecting said first pair of conductors to said second pair of conductors said first and second pairs of conductors meeting said third plane at substantially equal angles, and said third pair of conductors meeting said first and second planes at substantially the same angle,

20 whereby said jumper wires are of equal length and the spacing, length, and characteristic impedance of said transmission line is substantially constant throughout said turn.
